UNITED STATES PATENT OFFICE.

THOMAS S. HOMANS, OF BROOKLYN, NEW YORK.

DRAWING-TABLE.

No. 832,909.

Specification of Letters Patent.

Patented Oct. 9, 1906.

Application filed March 17, 1904. Serial No. 198,612.

To all whom it may concern:

Be it known that I, THOMAS S. HOMANS, a citizen of the United States, residing at Brooklyn, State of New York, have invented 5 certain new and useful Improvements in Drawing-Tables; and I do hereby declare the following to be a full, clear, and exact description of the invention, such as will enable others skilled in the art to which it appertains to make and use the same.

My invention relates to drawing-tables which are used more especially for the production of large-sized drawings, and particularly drawings which contain a great deal of detail work, such as designs of complicated machinery, &c.; and it consists of a certain new and useful construction for facilitating the production of such drawings, as herein-after fully explained.

It is now customary in mechanical drawing to use a large flat board on which the drawing-paper is fastened. It is obvious that the rear portion of such a board is more or less inaccessible from the front of the table, from which position the draftsman is obliged to work in order to be able to view his drawing correctly. This defect in the method becomes greatly augmented in cases where a great deal of detail is required, and 30 the attitude the draftsman must assume is necessarily awkward, irksome, and unhealthful, and the process of drawing consequently hindered.

The object of my invention is to obviate 35 this difficulty of reaching over to the rear portion of the table; and my invention consists, broadly, of a construction in which the table-top is movable and is composed and made up of narrow longitudinal sections 40 suitably hinged together and guided or constrained in such a manner that when the draftsman moves the rear portion forward the front portion will bend, curl, or otherwise move out of the way.

Having thus explained the essential features of my invention, I will now describe 45 my preferred construction, referring to the accompanying drawings, which show the upper part of the table only, it being understood that any suitable stand or substructure may be used.

Figure 1 is a side elevation of the device 50 with the left-hand frame and some other parts removed. Fig. 2 is a perspective view. Fig. 3 is a detailed side elevation of the front end with the left-hand frame re-

moved. Fig. 4 shows a portion of the front of the table in section. Fig. 5 is a detailed plan of one of the link-hinges.

Referring to Figs. 1 and 2, the frames 1 are joined together by the ties 2 and furnish bearings for the two revoluble shafts 3. Each of these shafts has two sprocket-wheels 4 fastened to it and situated just inside the framework, one on either side. 5 represents the longitudinal sections, preferably of wood, which make up the movable table-top. (See Figs. 3 and 4.) Said sections have lugs or tenons 6 on their ends, which fit into the recesses of the link-hinges 7 and are fastened 70 to them by screws 8. The links 7 are hinged together by the pins 9, which pins project beyond the links, partly for the purpose of engaging with the sprocket-wheels 4 and for the additional purpose of letting 75 their ends rest upon the ledges 10 of the frames 1. Preferably the links form two endless chains, one on each end of the movable table-top. The sections 5 are so shaped that they lie close together and form one 80 continuous surface when the chains are straightened out, yet by virtue of being beveled on the reverse side they clear each other when the chains are going around the sprocket-wheels 4. The ledges 10, forming 85 supports for the pins 9, prevent any sag to the working surface of the table. The top thus formed may be moved forward or backward at will, at the same time always preserving a continuous and rigid working 90 surface. The hand-wheel 11 is fastened to one of the shafts 3 in order to facilitate the moving of the table-top. Strips 12, which are part of the frames 1, furnish guides and rests for a T-square or any one of the commonly-used parallel-motion rulers.

The paper may be fastened directly to the table-top, as by thumb-tacks; but owing to discrepancies in workmanship and shrinkage of material and the difficulty of avoiding 100 crevices between the sections 5 I have preferred to cover the table-top with a flexible covering 13 stout enough to hold the points of the drawing instruments and to obviate any little irregularity of the table-surface.

It will be seen that the sections 5 of the table-top present sharp edges or corners at the front and back of the table where the chains are bent around the sprocket-wheels. These sharp edges have a tendency to crease 110 both the drawing-paper and the flexible covering 13 if the latter are allowed to cling to

the table-top and follow it around the curves. This is not objectionable at the rear part of the table, for the reason that the drawing-paper need never go around that portion; 5 but at the front I prefer to use a semicylindrical guard 14, which is secured to the frames 1. The covering 13 and the paper leave the movable table-top at the point where it begins to turn and slide over this guard. The 10 drawing-paper may either be fastened to the covering or may be fastened to the movable table-top by tacks, which go through the covering. In the latter case if the covering is made to go over the guard 14 tacks can be 15 used only at the top of the sheet of paper, so consequently I prefer to employ the flexible tapes 15, preferably of metal. These tapes may be endless and not attached to the table. Their purpose is to bind the covering and 20 paper to the table, and yet they are not tight enough to prevent the free movement of the covering over the guard.

I do not wish to limit myself to an endless construction of either chains, covering, 25 or tapes, for the reason that the movable table-top may be guided by grooves in the frames or by other suitable means and yet serve the purpose intended.

What I claim as new, and desire to protect 30 by Letters Patent, is—

1. In a drawing-table; the combination, with a suitable standard, of a movable table-top supported thereon; said table-top being composed of a series of sections connected 35 together by links forming endless chains; sprocket-wheels for controlling the movement of said chains; a flexible surface-covering for said table-top; a guard for keeping said covering away from the edges of the 40 table-top; and flexible tapes for binding said covering and the drawing-paper to the said table-top.

2. In a drawing-table, the combination with a suitable standard, of a movable table-top composed of a series of sections suitably 45 connected together and supported on the standard, means for guiding the movement of the table-top, a flexible surface-covering for the table-top, and a curved guard arranged beneath the covering to protect the 50 covering and the drawing-paper from the edges of the sections.

3. In a drawing-table, the combination with similar side frames, secured together 55 with a space between them, of parallel front and rear rotatable supports journaled between the frames, endless bands fitted to the supports, a series of parallel cross-strips secured on the bands, a flexible covering for 60 the strips, a curved guard arranged beneath the covering at the front end, endless flexible tapes arranged outside of the covering to

maintain the covering and drawing-paper in position.

4. In a drawing-table, the combination 65 with a suitable standard, of rotating supports journaled in the standard, a movable table-top composed of a series of connected sections, said table-top being carried on the supports, and endless flexible tapes arranged 70 around the table-top adjacent to each end to maintain the drawing-paper in position.

5. As a new article of manufacture, a drawing-table having a flexible, movable top, composed of a series of separate sections 75 having flat upper surfaces, and a smooth, flexible covering secured to said sections, directly to receive the drawing-paper, and in combination therewith a suitable frame, front and rear shafts journaled therein, 80 sprockets on the ends of said shafts, and endless chains on each side carried on said sprockets, the sections being secured at their ends to the respective chains.

6. In a drawing-table, the combination 85 with a frame, of a movable table-top composed of a series of sections arranged across the top and supported on the frame, a flexible covering for the table-top, and a curved guard at the front arranged beneath the cov- 90 ering as a protection from the edges of the sections.

7. As a new article of manufacture, a drawing-table having in combination a supporting-frame, a sectional table-top for receiving the drawing-paper movable on the frame, a convexly-curved guard arranged at the front of the table, and a flexible table-top secured on the sections to pass without the guard, to carry the paper over said guard. 100

8. As a new article of manufacture, a drawing-table having in combination a supporting-frame, a table-top movable on the frame for receiving the drawing-paper; said table-top consisting of a series of sections 105 covered by a flexible cover, and a convexly-curved guard, having a smooth outer surface, arranged at the front of the table, said guard having its upper edge substantially in alignment with the table-top and adjacent thereto at the line where the table-top begins to turn downwardly, to permit the drawing-paper to slide smooth and uncreased over the outer surface of the guard and be carried under the table and there maintained in 110 close contact with the table-top, while the flexible cover also passes without the guard, substantially as described and shown. 115

In testimony whereof I affix my signature in presence of two witnesses.
